UNITED STATES PATENT OFFICE.

FRANKLIN BROWN AND GEORGE SMITH, OF PHILADELPHIA, PENNSYLVANIA.

MACHINE FOR DYEING ARTICLES.

Application filed March 17, 1924. Serial No. 699,901.

To all whom it may concern:

Be it known that we, FRANKLIN BROWN and GEORGE SMITH, citizens of the United States, and residents of Philadelphia, in the county of Philadelphia and State of Pennsylvania, have invented certain new and useful Improvements in Machines for Dyeing Articles, of which the following is a specification.

10 Our present invention relates to an apparatus for dyeing articles such as hosiery, or the like.

The principal object of our invention is the provision of means whereby the articles 15 may be kept in agitation while in contact with the dyeing medium or liquor.

Another important object is the provision of such means as above, which will maintain the liquor itself in a constant state of agitation 20 so that pockets of various concentration will not be formed, with the result that the articles to be dyed will take the coloring evenly.

Still another object of our invention is 25 the provision of such means as above which will hold a plurality of articles simultaneously, yet which will allow articles to be removed from the dye bath as may be desired, and which will be simple in construction, efficient in operation and of low cost to manufacture.

To this end our invention includes a tank of any desired construction or configuration 30 to hold the dye liquor, to the top of which are attached supporting members carrying 35 between themselves a rotatable axle which may be caused to rotate by any suitable mechanism, with which this invention is not concerned. The rotatable axle is provided with 40 flanges or outwardly extending portions near its ends and means to hold the articles to be dyed are removably attached between said flanges or outwardly extending portions. It has been found expedient to utilize 45 web bags to hold the articles to be dyed, and in the preferred embodiment of our invention we employ a plurality of rods detachably held in parallelism to the axle and between the flanges at its ends. A rod is 50 threaded to the web bag which contains the article to be dyed, and then put in position. The mechanism may now be started, or starting be postponed until the entire number 55 of rods with which the axle is provided are each supplied with their bag. The axle is suspended from the cover of the tank to

an extent which will allow the bags to be entirely submerged in the dye liquor at all times.

It will be quite apparent that as these 60 bags rotate they will, of themselves act as paddles, which will keep the dye liquor in a constant state of agitation which will prevent formation of pockets or spots in the dye liquor of greater concentration than 65 others.

We have illustrated in the accompanying drawings, the preferred embodiment of our invention, although it is understood that we 70 do not wish to be limited thereto.

In these drawings:—

Figure 1 is a sectional elevation through the dye tank, showing the rotating mechanism.

Fig. 2 is a side elevation of a modified 75 form of the device.

Fig. 3 is a plan view of Fig. 1.

Fig. 4 is a sectional elevation of the rotating mechanism.

Fig. 5 is a detail.

Referring now with particularity to the drawings, we have illustrated the tank diagrammatically at 1, having a cover 2 of any desired form, which, in this instance, is provided with a trap 3 for viewing the articles 85 during the process of dyeing.

Attached to the under side of the cover 2 we provide depending journal irons 4 and 5. An axle shaft shown at 6 is provided with flanges 7 intermediate each end of the axle 90 6, although in proximity to the ends thereof for a purpose to be more fully described hereinafter. The axle 6 is journaled in the irons 4 and 5, as indicated by the bearings 8 and 9 respectively. The axle 6 extends 95 beyond the bearing 9 and has attached thereto a gear element 10 which is in mesh with a similar gear 11, also mounted on the iron 5 as at 12. This upper gear 11 may be driven from without the tank by any suitable means, not shown.

The flanges 7 are perforated near their periphery as at 13, that flange adjacent the gear 10 having a plate 14 secured thereto which covers the perforations on that side. 105 The flange 7 adjacent the bearing 8 is also provided with a plate 15 which, in this instance is not attached to the flange but has a central aperture 16 through which the end of the axle 6 passes.

A collar 17 is attached to the shaft 6 adjacent the bearing 8 for the purpose of pre-

venting lateral slip of the shaft during the operation of the device. A coil spring 19 is held between the collar 17 and the plate 15, and exerts pressure against the latter forcing this against the outer face of the flange 7.

Various means to hold the articles that are to be dyed will occur to those skilled in the art, but we have found it convenient to utilize short lengths of rods 20, of any desired material, held in corresponding perforations in the two flanges 7 on the axle 6. In order to insert or remove a rod from the device, the end of the rod socketed in a perforation in the flange 7 adjacent the spring-pressed plate 15, is forced against the plate which gives under action of the spring and the opposite end of the rod may then be placed in the corresponding perforation in the opposite flange 7, the spring 19 forcing the plate 15 against the flange 7, which effectively retains the rod 20 in position. This may be repeated as often as desired until all the perforations in the two flanges 7 are filled with rods. Before placing these rods in position, webbed bags 21 holding the articles 22 to be dyed, are threaded upon the rods so that they appear as illustrated.

Obviously in place of solid flanges 7 we may make use of extended arms 23 projecting outwardly in a radial manner from the axle 6 and rods or other holding means attached to the ends of the arms 23.

In operation of the preferred form of the device, the articles having been placed in their bags and the bags upon the rods 20, the rotating mechanism is started and the bags 21 containing the articles 22 are made to rotate about the axle 6. This effectively keeps the dye liquor in constant agitation while at the same time bringing the articles to be dyed in contact with the liquor at all parts of the tank.

In case the bags of substantially the same size as that illustrated at 21 are held on extending arms 23, gravity would hold them in substantially vertical position on those, so that as the rod 20 to which the bag is

attached reaches the position directly over the axle 6, the bag would pass between the rod and the axle.

In the claim wherein we speak of a flange on the axle, it is to be understood that this may also include an outstanding arm, as this is clearly an equivalent of a solid flange.

By reason of these instrumentalities it will be apparent that the usual mechanism necessary to rotate the whole drum or tank which contains the dye liquor may be dispensed with and very simple rotating mechanism substituted therefor.

It will also be seen that the articles to be dyed are positively held in place and cannot float loosely about the dye liquor to become tangled in the mechanism or with other undesirable results. By holding the articles in the bag and attaching the bag securely to the rotating axle, the articles to be dyed are kept from contact with the metallic sides of the tank or other material of which the liquor container is made.

It is understood that the tank is to be filled with the dye liquor to the point so that the articles will be completely submerged at all points of the operation.

It is to be understood that various forms of receptacles to hold the articles to be dyed might be employed, which will rotate about their supporting member as the mechanism rotates, in addition to the receptacle shown.

Having thus described our invention, what we claim is:—

In a dyeing machine the combination of a rotatable member, rods held thereon, containers held on said rods and adapted to receive articles to be dyed, a flange on each end of said rotatable member, said rods being held in said flanges, and a spring pressed plate retaining said rods in said flanges.

In testimony whereof, we affix our signatures.

FRANKLIN BROWN.
GEORGE SMITH.
